HIGH FREQUENCY ELECTRON DISCHARGE
DEVICE

Oskar Hell, Ludwigshafen-on-the-Rhine, Germany, assignor to Radio Corporation of America, New York, N. Y., a corporation of Delaware

Application February 23, 1935, Serial No. 7,894.
Renewed August 10, 1939. In Germany February 23, 1934

24 Claims. (Cl. 250—27.5)

This invention relates to a method of and apparatus for producing short electromagnetic waves.

As is well known, undamped short electromagnetic waves are produced either by the back coupling method utilized in connection with long waves, or by an arrangement utilizing oscillating electrons, for example as proposed by Barkhausen and Kurz, or by means of an arrangement utilizing revolving electrons, such as the magnetron.

The present invention is based on an entirely novel principle of short wave generation, and neither back coupling, nor revolving electrons are utilized therein.

In order that the invention may be well understood, a few fundamental definitions will be first of all referred to.

The Faraday cage is a hollow metal body. It has the property that an electric charge located in its interior has the same relation towards the exterior as if it were located on the metal. Therefore, an electron located in the hollow space of the Faraday cage has the same effect outwardly as if it had settled on the metal itself, and hence movement of an electron within the cage has no effect on the cage and changing voltage on the cage has no effect on an electron within the cage since the interior of the cage is a field free space.

It is furthermore known that an electron in flight approaching a conductor or receding therefrom represents an electric current away from or towards said conductor.

The invention will now be explained, remembering the above definitions, by reference to Fig. 1 of the attached drawings, it being understood that this figure has for its sole object to facilitate explanation of the principle of the invention.

An electron moves on the dotted path through a Faraday cage 2. On its way up to the point 3 it represents a negative current upon the Faraday cage. As soon as the electron has arrived at 3 this current suddenly ceases. While the electron moves within the Faraday cage from 3 to 4 no observation can be made outside. The effect is the same as if the electron had settled on the metal of the cage. When, however, the electron leaves the Faraday cage at 4 there will be a sudden current in the opposite direction, since the electron is now receding. It is understood of course that a circuit is connected between the cage 2 and cathode 5 and collector 6, and that proper voltage sources are connected between cathode 5, electrode 2 and collector 6

to make electrons move from cathode 5 to collector 6.

In the whole of these considerations the most important factor is the time during which the electron moves in the cage. For brevity this period of time will hereinafter be referred to as "period of dwell." The length of the period of dwell is proportional to the distance 3—4 and inversely proportional to the velocity of the electron. If the distance 3—4 is a fixed one, the period of dwell or transit time of the electron through the hollow electrode depends solely upon the velocity of the electron. If the Faraday cage is caused to be strongly positive as compared to the electron emitting cathode 5, then electrons of great velocity will fly therethrough and the period of dwell will be very short. If the Faraday cage is caused to be only slightly positive as compared to the cathode, then slow moving electrons will fly therethrough and the period of dwell will be very long. If a very rapidly alternating potential is applied to the Faraday cage in the form of oscillations of very high frequency, then the period of dwell will depend upon the potential to which the Faraday cage is raised at the instant the electron enters. While the period of dwell elapses the potential of the Faraday cage is altered, so that when the electron emerges therefrom the cage will be at a different potential.

The most important fact which may be deduced from the preceding considerations is as follows: Electrons entering the Faraday cage during the negative half period are slow and will not leave the cage until the following positive half period. Electrons entering the Faraday cage during the positive half period are fast and will mostly leave the cage during the same half period.

More specifically if an unmodulated stream of electrons is directed through the hollow electrode and assuming an alternating voltage is applied to the electrode, the electrons approaching the electrode will be either accelerated or decelerated depending upon the voltage at the moment applied to the electrode, that is, electrons will be accelerated if the voltage on the electrode is beginning or is in its positive half cycle or will be decelerated if the voltage is beginning or is in its negative half cycle. With any hollow electrode, since the space within the electrode is all at the same potential, that is a field free space, the speed of the individual electrons through the electrode will be that which the individual electrons have upon entering the hollow electrode, that is, the accelerated electrons will

continue to move rapidly at a constant speed through the electrode and the decelerated electrons at a slow constant speed through the tubular electrode. The result is that the fast electrons overtake the slow electrons causing a resulting change in the density of different portions of the electron beam, with a dense cloud of electrons separated by sections where the electrons are few. The extent to which this action takes place is determined by the length of the tube and the transit time or speed of the electrons. This space within the hollow electrode may thus be considered a space where the electrons drift to form the dense and rarefied portions of the beam and the result is a density modulation of the electron stream.

Considering now the electron balance of the Faraday cage the result obtained is as follows: In the negative half period the ingress of electrons is predominant. In the positive half period the egress of electrons is predominant. But a negative body becomes more negative by the ingress of electrons and a positive body becomes more positive by the egress of electrons. Thus, the high frequency alternating potential applied to the Faraday cage is aided by the electrons. The electrons will lend energy to the high frequency oscillation and will themselves maintain the oscillation of any oscillating circuit connected to the electrode. It is obvious that the alternating potential introductory mentioned in connection with these considerations as being applied from outside is not required, the oscillations will start automatically as in any generator. The presence of an alternating potential has been assumed merely to facilitate the understanding of the invention.

Further and in more detail, as the electrons leave the hollow electrode, depending upon the cycle of the applied voltage, the electrons will either give up or take away energy from the electrode. If the electrons leave during the positive portion of a cycle, they are slowed down and give up energy to the electrode, thus producing an inductive output effect and inducing a voltage in the electrode. On the other hand, if the electrons leave during the negative portion of the cycle, they are accelerated and absorb energy from the electrode. Normally this hollow electrode when incorporated within a tube of the kind under consideration has such length and the voltages applied are such that there is a net transfer of energy from the electrons to the electrode, which if applied to an oscillating circuit connected to the electrode may be used to furnish the modulating voltage to the electrode. On the other hand, if the electrons are first modulated before being directed through the tube, the electrode can be used as an inductive output electrode. The frequency at which the electron stream is modulated, the natural period of frequency of oscillation of the tubular electrode and its associated circuit, and the transit time of the electrons may be so adjusted that the oscillating circuit will receive energy from the modulated electron stream.

It will be apparent from the foregoing that according to this invention apparatus for producing short electromagnetic waves comprises, in an electron discharge tube, hollow metal bodies adapted to form electrically oscillating electrodes and caused to perform such oscillation by electrons flying therethrough.

75 Some details will now be described which ap-

pear to be of advantage in the practical embodiment of the invention.

In the production of very short waves the flight of the electrons to the hollow metal body and the flight of the electrons away therefrom must be very rapid. This may be achieved by disposing between the cathode and the hollow metal body, or hollow metal body and the anode a strongly positive grid (accelerating electrode), or by disposing a positive grid around the hollow body. 10

Preferably, the electrons are caused to form a pencil or beam by providing a negative electrode surrounding the cathode after the manner of a Wehnelt cylinder. This makes it possible to utilize smaller hollow metal bodies and the capacity 15 of same will be small.

The said negative electrode or a control grid may be utilized to control the flow of the electrons. This will enable the waves to be generated to be conveniently modulated by an oscillating circuit connected between the cathode and control grid. 20

A double system, with two opposing hollow bodies, may be disposed in a single electron discharge tube. To these hollow bodies may be connected Lecher wires or some other oscillating circuit. 25

The velocity of the electrons which have passed through the hollow metal body differs. A number of them passes through the hollow body practically without loss, a small number of them loses speed. Therefore, if the anode of the electron discharge tube is made strongly positive, all the electrons will reach it. But they will strongly heat the anode, so that the tube will operate 30 with poor efficiency. If on the other hand, the anode is caused to be only slightly more positive than the cathode, the heat generated will be very slight. But in this case the small number of electrons having a low velocity will not reach the 40 anode, they will pass to the grid surrounding the hollow metal body instead, so that said grid will be unnecessarily heated. 35

These defects may be eliminated by disposing the anode not at right angles but slantly to 45 the flow of the electrons. The slow electrons are thereby thrown to one side and may be intercepted by a further auxiliary anode. Instead of the slanting anode V-section anodes may be employed. The said auxiliary anode may surround 50 the whole system cylindrically. It picks up all energy losses and, if required may be cooled from outside by water, air or the like, so that even very large power tubes become manageable. 55

The heat generated in the interior of the tube by the impact of very fast electrons with the hollow body, the positive grid and the anode plate proved to be a certain defect of the method described in the foregoing. To remove this defect it is proposed to provide the hollow metal body 60 acting as electrically oscillating electrode with apertures corresponding to the section of the pencils of electrons. These apertures facilitate the ingress and egress of the directed pencils of rays of electrons and correspond in shape to the section of the narrow strongly collected rays of electrons, which may be of slit or point section that is of rectangular or circular cross section. The strongly positive grids (accelerating electrodes) are also preferably partly or wholly replaced by electrodes which are provided with apertures for the passage of electrons or rays of electrons, said apertures again corresponding to the section of the rays of electrons. 65

70 The provision of apertures in the hollow metal 75

bodies and in the positive grids has for a result that practically no electrons impinge upon the metal parts.

With a view to concentrating the rays of electrons and to reducing the capacity between the accelerating electrodes and the hollow metal bodies it is advisable to provide the apertures of the hollow metal bodies and of the accelerating electrodes with projections. These projections may be in the form of funnels disposed either vertically or at an angle relatively to the said apertures.

In carrying into effect the method according to the invention it appeared to be of particular advantage to provide the braking and intercepting electrodes (anodes) in the form of a plurality of parallel metal plates insulated one from the other and disposed in the direction of the electron rays, said plates also having apertures corresponding to the section of the rays of electrons. The plates are not disposed at right angles but in a slightly inclined position relatively to the direction of the electron rays and the potential of successive plates is gradually more and more negative. As a result, only slow electrons will impinge upon the metal. The greater the number of the plates employed the smaller will be the heat generated by the impact of electrons.

In carrying into effect the present method it is of advantage not to employ a very high vacuum in the electron discharge tubes utilized, so that narrow pencils of high electron current may be obtained. In this manner a certain ionic space charge is obtained which compensates and even over-compensates the space charge due to the electrons.

Because of the high mass of the positive ions their inertia will be so high that the ions can be considered stationary as far as the effects of high frequency fields are concerned. Therefore, the presence of a small amount of gas will enhance the operation of the high frequency tube by neutralizing the detrimental effects of the electronic space charge.

The nature of the invention will now be explained by reference to the accompanying drawings, it being understood that it is not intended thereby to limit the invention to the specific embodiments illustrated in the drawings. It is obvious that those skilled in the art will be able to devise other embodiments without departing from the spirit of the present invention.

Figs. 2, 3 and 4 are diagrammatic cross sectional views of apparatus constructed according to the invention.

Fig. 5 is an elevation of apparatus shown in Fig. 4.

Figs. 6, 7 and 8 are diagrammatical cross sectional views of the hollow metal body and the accelerating electrode.

Fig. 9 is a diagrammatic representation of the complete electrode arrangement.

Referring now to Figs. 2 and 3, two plates 8 forming the negative electrode are arranged adjacent to the cathode 5. Said negative electrode 8 focuses the electrons emitted by the cathode into two oppositely disposed beams and directs said electrons. The electrons are given a very great velocity by the positive grids 1 (accelerating electrodes) and fly transversely through the hollow metal bodies 2 to the anodes 6, producing oscillations in these metal bodies 2.

More specifically the electrons from the cathode 5 are formed into beams by the negatively

biased focusing electrodes 8 which can also be used as a control electrode as pointed out above. Each beam is directed through an accelerating and shielding element or grid 1, a hollow inductive output electrode 2, a second accelerating and shielding element or grid 7 and then collected by an auxiliary collecting electrode or anode 6. The electrodes may have various shapes but in each the output electrode is shielded from the cathode by the accelerating or shielding electrode, and from the collector by a second accelerating or shielding electrode. As pointed out above, electrons which approach the hollow tubular electrode 2 during the negative half cycle are slowed down and leave during the next positive half cycle whereas electrons approaching the electrode 2 during a positive half cycle are accelerated and leave the hollow electrode during the same half cycle. Thus the velocity of the electrons is modulated in the space between the first accelerating electrode 1 and the hollow tubular electrode 2. After entering the space within the hollow electrode the electrons drift through at the velocity which they had on entering the electrode since no field influences their movement through the electrode. As a result the fast electrons overtake the slow electrons within this drift space and leave the tubular electrode 2 in more or less well defined groups so that portions of the beam are more dense than other portions. This results in a change of density of different portions of the electron stream. Since the electrons leave the electrode during the positive half cycle they tend to slow down due to the positive voltage on the hollow electrode but on doing so give up energy to the electrode 2 so that any oscillating circuit connected between this electrode and the accelerating electrodes 1 receives energy from the decelerated electrons. It is for this reason that the device will remain in oscillation and act as an oscillating generator.

In Fig. 3, in addition to the anodes 6 which in this case are disposed at an angle relatively to the direction of the rays of electrodes, there are provided auxiliary anodes 9 (braking and intercepting anodes) which intercept the slow electrons, that is slow electrons having less energy than the faster electrons are deflected by electrode 6 at low positive potential to the collector electrode 9 at the higher positive potential.

Fig. 4 illustrates how the additional anode 9 may be disposed to surround the whole system in the form of a metal shell.

Fig. 5 also illustrates the connection of the hollow metal bodies acting as oscillating electrodes to the Lecher wires 10.

Figs. 6, 7, 8 and 9 show various possible embodiments of the hollow metal bodies and of the accelerating electrodes, the hollow metal bodies 60 being indicated at 2 and the accelerating electrodes being indicated at 1. The directed pencils of electrons pass through the apertures 11 of the hollow metal body and the apertures 12 of the accelerating electrodes in the direction of the arrow shown. The hollow metal bodies are preferably cylindrical, but they may be composed of plane plates, as shown in Figs. 7 and 9. If the pencil or beam of electrons is of point or circular section rather than rectangular as in the case of a ribbon shaped beam, the said hollow metal bodies may be structures revolutionarily symmetrical to the direction of the pencil of electrons that is the electrodes 2 may be tubular members. The projections of the hollow metal

bodies are indicated at 13, and those of the accelerating electrodes at 14. The projections may be disposed at right angles or slantingly with respect to the corresponding apertures of the hollow bodies or accelerating electrodes.

In Fig. 9 the cathode emitting the electrons is indicated at 5 and as shown it is surrounded by the negative electrode 8 which focuses the electrons in a pencil or beam and directs them. The electrons are accelerated by the positive electrode 7 and after passing through the hollow metal body 2 impinge upon the inclined braking or intercepting electrodes 6. The plate first passed by the electrons is strongly positive, and each successive plate is less positive than the preceding one. The electrons flying through the apertures of the plates are gradually braked and caused to turn around. The electrons entering at a low speed are caused to turn around sooner, the fast electrons later, having turned around the electrons are deflected laterally owing to the slanting disposition of the plates and fall on the rear face of the plate through which they have just passed. The path of the electrons is indicated in dotted lines.

In Figure 10 the electron discharge device comprises a cathode 5' and beam forming electrode 8' adjacent the cathode. The collector electrode 6' has positioned between it accelerating electrodes 7' and hollow electrode 2'. The electron stream from the cathode 5' may be modulated by a control grid 9' positioned between the cathode 5' and the first accelerating electrode 7', the modulating signal being applied between the cathode 5' and grid 9' by an input 10'. The output 11' is connected as suggested above to the output electrode or hollow electrode 2'. In this arrangement the electron beam may be modulated before it enters the space between the two accelerating electrodes. This permits the use of the tube as an amplifier as well as an oscillator.

It is obvious that instead of utilizing the electrodes 5 and 8 for forming the pencils of electrons electrode systems, such as employed in X-ray tubes and Braun tubes, may be utilized.

It is preferred to connect two systems of electrodes to one Lecher system or some other oscillating circuit, which may be disposed within the tube, if so desired.

50 What I claim is:

1. An electron discharge tube for producing short electromagnetic waves, comprising cathode means, negative electrodes adjacent to said cathode means, accelerating electrodes having apertures, hollow metal bodies each having apertures and connected to a lead wire and disposed between said accelerating electrodes, and electron intercepting anodes, said apertures in said hollow metal bodies and in said accelerating electrodes being of a shape corresponding to the section of the pencil of electrons, and said electron intercepting anodes comprising a plurality of parallel plates insulated from one another, said plates being disposed at an angle to the direction of the pencil of electrons and having apertures corresponding in shape to the section of the pencil of electrons, and said apertures in said plates being disposed in the direction of the pencil of electrons.

2. An electron discharge tube for producing short electromagnetic waves comprising an exhausted envelope, cathode means within said envelope for emitting electrons, anode means within said envelope for intercepting said electrons, hollow metal bodies each having apertures and being connected to a lead wire and disposed be-

tween said cathode means and anode means in the path of said electrons, and accelerating electrodes provided with apertures mounted between said hollow bodies and said cathode means and said anode means respectively.

3. An electron discharge tube for producing short electromagnetic waves comprising an exhausted envelope, cathode means within said envelope for emitting electrons, anode means within said envelope for intercepting said electrons, negative electrodes adjacent to said cathode means, hollow metal bodies each having apertures and being connected to a lead wire and disposed between said cathode means and anode means in the path of said electrons, and accelerating electrodes provided with apertures mounted between said hollow bodies and said cathode means and said anode means respectively.

4. An electron discharge tube for producing short electromagnetic waves comprising an exhausted envelope, cathode means within said envelope for emitting electrons, anode means within said envelope for intercepting said electrons, negative electrodes adjacent to said cathode means to collect the emitted electrons to form an electron beam, hollow metal bodies each having apertures and being connected to a lead wire and disposed between said cathode means and anode means in the path of said electrons, and accelerating electrodes provided with apertures mounted between said hollow bodies and said cathode means and said anode means respectively, said apertures in said hollow metal bodies and in said accelerating electrodes being of a shape corresponding to the cross section of the electron beam.

5. An electron discharge tube for producing short electromagnetic waves as claimed in claim 4, in which said hollow metal bodies are provided with funnel shaped projections adjacent to said apertures in said accelerating electrodes.

6. An electron discharge tube for producing short electromagnetic waves comprising an exhausted envelope, cathode means within said envelope for emitting electrons, anode means within said envelope for intercepting said electrons, a negative electrode adjacent to said cathode to collect the emitted electrons to form an electron beam, hollow metal bodies each having apertures and being connected to a lead wire and disposed between said cathode means and anode means in the path of said electrons, and accelerating electrodes provided with apertures mounted between said hollow bodies and said cathode means and said anode means respectively, said apertures in said hollow metal bodies and in said accelerating electrodes being of a shape corresponding to the cross section of the electron beam.

7. An electron discharge tube for producing short electromagnetic waves comprising an exhausted envelope, cathode means within said envelope for emitting electrons, anode means within said envelope for intercepting said electrons, said anode means being slantingly mounted to the path of the electrons, auxiliary anode means for intercepting electrons having a low velocity, negative electrodes adjacent to said cathode to collect the emitted electrons to form an electron beam, hollow metal bodies each having apertures and being connected to a lead wire and disposed between said cathode means and anode means in the path of said electrons, and accelerating electrodes each provided with an aperture mounted between said hollow bodies and said cathode means and said anode means respectively, said apertures in said hollow metal bodies and in said

accelerating electrodes being of a shape corresponding to the cross section of the electron beam.

8. An electron discharge tube comprising an evacuated envelope enclosing a hollow metal body having an unobstructed opening through it and a lead extending outside said envelope, a cathode outside of and at one end of said body, an anode outside of and at the other end of said body and having an aperture coaxial with the opening in said hollow metal body, means for concentrating the electron discharge from said cathode to said anode into an electron beam directed through the aperture in said anode, and intercepting electrodes beyond said anode comprising a plurality of parallel insulated plates each having an aperture and mounted with said apertures aligned with the aperture in said anode to be in the path of said electron beam, said plates being inclined to the path of said beam beyond said anode.

9. A short wave electron discharge tube comprising an evacuated envelope enclosing means including an electron emitting cathode for forming an electron discharge from said cathode into an electron beam, electron intercepting electrodes comprising a plurality of insulated metal plates inclined to the direction of and mounted to intercept the electron beam, spaced accelerating electrodes between said means and said intercepting electrodes and having aligned apertures in the path of the electron beam, a hollow metal body connected to a lead wire and disposed between and with its ends near said accelerating electrodes and having apertures aligned with the apertures of said accelerating electrodes, said apertures in said hollow metal body and in said accelerating electrodes being of a shape corresponding to the cross-section of the electron beam.

10. A short wave electron discharge tube as defined in claim 9 in which the hollow body and the accelerating electrodes have at the apertures tubular projections surrounding the apertures.

45 11. A short wave electron discharge tube as defined in claim 9 in which the intercepting electrodes are parallel and have apertures corresponding in shape to the cross-section of the electron beam and disposed in the path of the electron beam.

50 12. An electron discharge device including an evacuated envelope containing a cathode for supplying electrons, means for forming said electrons into a beam, a collector electrode for receiving electrons in said beam and velocity modulating means for accelerating and decelerating said electrons, said velocity modulating means including a hollow tubular conducting member adapted to have alternating potentials of high frequencies applied thereto during operation of said electron discharge device and an apertured electrode adjacent each end of said hollow tubular conducting member and positioned between said hollow tubular conducting member and all other electrodes within said envelope.

55 13. An electron discharge device including an evacuated envelope containing means including a cathode for forming electrons from said cathode into a directed beam, a collector electrode for collecting electrons in said beam, an apertured electrode adjacent said cathode, a hollow electrode between said apertured electrode and said collector electrode for providing a field free space through which said beam is directed and electrode means including said hollow electrode

for subjecting said beam to a high frequency field before entering said hollow electrode and after leaving said hollow electrode, and a second apertured electrode between said hollow electrode and said collector electrode.

60 14. An electron discharge device including an evacuated envelope having a gaseous atmosphere therein and containing a cathode for supplying electrons, means for forming said electrons into a beam, a collector electrode for receiving electrons in said beam and velocity modulating means for accelerating and decelerating said electrons, said means including a hollow tubular member adapted to have alternating potentials of high frequency applied thereto during operating of said electron discharge device, and an apertured electrode adjacent each end of said hollow electrode and positioned between said hollow electrode and all of the other electrodes within said envelope.

65 15. A short wave electron discharge device comprising an evacuated envelope enclosing a velocity modulating means comprising a hollow metal body, means adjacent one end of said hollow metal body and including an electron emitting cathode for forming the electron discharge from said cathode into an electron beam directed through said hollow metal body, and a collector adjacent the other end of said hollow metal body in the path of the electron beam which is to be passed through said hollow metal body, and an apertured electrode adjacent each end of the hollow metal body and each having an aperture in the path of the electron beam through said hollow metal body, said collector being inclined to the path of the electron beam through the apertured electrodes.

70 16. An electron discharge device including an evacuated envelope containing a cathode for supplying electrons, means for forming said electrons into a beam, a collector electrode for receiving electrons in said beam and velocity modulating means for accelerating and decelerating said electrons, said means including a hollow tubular conducting member adapted to have alternating potentials of high frequency applied thereto during operation of said electron discharge device, and an apertured electrode adjacent each end of said hollow tubular conducting member and positioned between said hollow tubular conducting member and all of the other electrodes within said envelope.

75 17. An electron discharge tube for use at high frequencies including a cathode for supplying electrons, means for forming said electrons into a beam and a collector electrode for said beam, electrode means between said cathode and collector electrode for applying a high frequency alternating electric field to said beam, part of said electrode means comprising a hollow body for providing a field free space through which the beam passes after being subjected to said high frequency alternating field, and electrode means between said collector electrode and said hollow body for abstracting energy from said beam after its passage through the field free space and before reaching said collector electrode.

80 18. An electron discharge tube for use at high frequencies including a cathode for supplying electrons, means for forming said electrons into a beam and a collector electrode for said beam, velocity modulating means between said cathode and collector electrode including an apertured electrode and a hollow electrode for applying a high frequency alternating field to said beam,

said hollow electrode providing a field free space through which the beam passes after being subjected to said high frequency alternating field, and electrode means including said hollow electrode and a second apertured electrode for abstracting energy from said beam after its passage through the field free space and before reaching said collector electrode.

19. An electron discharge tube for use at high frequencies including a cathode for supplying electrons, means for forming said electrons into a beam, a collector electrode for said beam, a hollow electrode positioned between said cathode and collector electrode through which said beam is directed, a control electrode between said cathode and hollow electrode for modulating the beam of electrons, an apertured electrode positioned between said control electrode and said hollow electrode and a second apertured electrode between said hollow electrode and collector electrode, said hollow electrode and said first apertured electrode defining a high frequency field space through which said beam is to pass before entering said hollow electrode, and said hollow electrode and said second apertured electrode defining a second high frequency field space through which said beam is to pass after leaving said hollow electrode.

20. An electron discharge device for producing short electromagnetic waves, including an evacuated envelope, cathode means within said envelope for supplying electrons in oppositely disposed beams, anode means within said envelope for intercepting said beams of electrons, a hollow metal body disposed in each beam path between said cathode means and said anode means, and accelerating electrodes provided with apertures mounted between each of said hollow metal bodies and said cathode means and said anode means respectively.

21. A short wave electron discharge tube including an evacuated envelope containing a hollow metal body, means adjacent one end of said hollow metal body and including an electron emitting cathode for forming said electron discharge from said cathode into an electron beam directed through said hollow metal body, a collector electrode mounted adjacent the other end of said hollow metal body in the path of the

electron beam which is to be passed through said hollow metal body and an apertured member adjacent each end of said hollow metal body and between said hollow metal body and all other electrodes in said tube, said apertured members and said hollow metal body defining spaces in which said electron beam is to be subjected to high frequency alternating electric fields, the apertures in said apertured members lying in the path of the electron beam through said hollow metal body.

22. An electron discharge device for use at high frequencies having a cathode for supplying electrons, means for forming said electrons into a beam and a collector electrode for said beam, a first apertured electrode adjacent said cathode, conductive means surrounding the electron path and located between said first apertured electrode and said collector electrode, said conductive means having a surface next adjacent said first apertured electrode defining therewith a high frequency field space, and a second apertured electrode between said conductive means and said collector electrode.

23. An electron discharge device for use at high frequencies including a cathode for supplying electrons, means for forming said electrons into a beam, and a collector electrode for said beam, a pair of apertured members positioned between the cathode and the collector through which said beam of electrons is directed, and a velocity modulating member surrounding the beam between said apertured electrodes for modulating the beam.

24. An electron discharge device for use at high frequencies and including a cathode for supplying electrons, means for forming said electrons into a beam, and a collector electrode for said beam, a first electrode means between said cathode and collector electrode for applying independently of said cathode a high frequency alternating field to said beam for velocity modulating the beam, and a second electrode means between said first electrode means and said collector electrode for abstracting energy from said beam after the application of the high frequency electric field to said beam and before said beam is collected by said collector electrode.
